REMOTE CONTROL SYSTEM FOR CRANES

Remi Bollaert, Oakland, Calif., assignor to Westinghouse Electric Corporation, East Pittsburgh, Pa., a corporation of Pennsylvania

Application March 27, 1946, Serial No. 657,391

8 Claims. (Cl. 172—179)

1

My invention relates to electric control systems for traveling cranes and has for its object to permit a considerable reduction in the number of trolley wires and appertaining accessories heretofore necessary for controlling the trolley and hoist motors of such cranes from an operator's place remote from the crane trolleys.

An example may elucidate this objective of my invention. Assume a bridge crane having two trolleys with a trolley propulsion motor and a hoist motor on each trolley. The appertaining controls are equipped with a relay system that comprises one forward and one reverse contactor and two accelerating contactors for each motor. Auxiliary timing and sequence relays may also be provided, but these do not enter into the discussion of the required number of trolley wires. If, for example, both motors are three-phase wound-rotor motors, then the crane control system would conventionally be designed in one of the two following ways.

1. The motors only might be put on the main trolley structures and the main power wires carried back to the operator's position in the cab. All of the control equipment is then in the cab. In this case it is necessary to bring three primary and three secondary conductors from each motor making a total of 24 trolley wires. It is possible to make certain wires common to several motors but at best three or perhaps six trolley wires can be eliminated by this expedient.

2. It is possible to mount the control equipment directly on the trolley structures and eliminate the necessity of carrying the individual motor currents on trolley wires. With this arrangement it is necessary to have three main line conductors from which all of the motors are fed and to carry the control wires to the master switches in the cab. Conventional practice is to have one wire common to all of the control contactor coils with individual wires extending to the opposite terminals of the contactor coils. Since sixteen coils are to be operated, it is necessary to have sixteen control wires, one common control wire, and three main line wires making a total of twenty.

In contrast to these known systems, it is the aim of my invention to achieve the same control performance with a much smaller number of trolley wires, thus reducing the space taken up by these wires and the amount and space of the insulating and other equipment needed to accommodate these wires along the path of travel of the crane trolleys.

To this end, and in accordance with my inven-

2

tion, I mount the relays of the control system directly on the trolley structure and energize each group of relays appertaining to a particular motor through a circuit means, such as a transformer, which is also mounted on the trolley. All relays of each individual relay group have a common lead connected to one pole of a separate output circuit of the circuit means or transformer, while the other pole of this output circuit extends through a trolley wire to master control contacts at the operator's place and, by means of these contacts, is selectively connected to one of a group of trolley wires of which each is in connection with one of the respective relays of the one relay group and also in connection with one of the respective relays of the other relay group. While these features of my invention will be more fully understood from the following description of the embodiment illustrated in the drawing, it may here be mentioned, that, by virtue of the above-mentioned features, in the above discussed example of a two-trolley crane with four contactors for each motor, only eight control trolley wires in addition to the three power trolley wires are required, making a total of only eleven wires as compared with the twenty-four or twenty wires above mentioned. A still more appreciable reduction in the number of trolley wires is, of course, obtained in systems with more than four control relays for each motor or with more than two trolleys.

In the drawings:

Figure 1 shows diagrammatically a bridge crane with two trolleys.

Fig. 2 is a simplified circuit diagram representing the control panels of the two trolleys in conjunction with the appertaining trolley wires and the master control devices to be actuated by the operator in the control cab of the crane, and

Fig. 3 is a more detailed circuit diagram showing the complete control equipment for one of the two trolleys.

According to Fig. 1, the wheels A of the bridge structure run on rails C so that the structure is movable perpendicular to the plane of illustration. The drive means for propelling the bridge in this direction are irrelevant to the present invention and hence not illustrated. The bridge structure carries rails D on which two trolleys E1 and E2 are movable transverse to the traveling direction of the bridge structure. Each trolley has two motors H1, T1 and H2, T2, respectively. The motors H1 and H2 are geared to the cable drum of the hoisting equipment and serve

to hoist and load the respective cables F1 and

F2. The motors T1 and T2 are geared to the wheels of the respective trolleys for propelling them individually along the rails D. Each trolley has a control panel P1 or P2 which contains all relays and associated electric equipment for controlling the operation of the two trolley motors. Eleven trolley wires denoted by 1 through 11 extend along the path of the trolley motion, and are mounted on insulators I. These trolley wires connect the control panels of the two trolleys with the master control equipment located in the operator's cab K.

The four motors in the illustrated example are of the three-phase wound-rotor type. They receive their primary excitation through the trolley wires 1, 2, 3 which are connected to a suitable source of alternating-current voltage. The remaining trolley wires 4 through 11 serve to control the relays of the trolley control panels in such a manner as to permit an individual operation of the motors.

According to Fig. 2, each control panel P1 and P2 is equipped with a circuit device for providing a step-down voltage for a relay equipment. This device consists of a transformer N1 or N2 which has two secondary windings Q1 and R1 or Q2 and R2. The primary terminals of the transformers N1 and N2 are attached to collectors which engage the power supply wires 1 and 3. The secondary windings Q1, R1, Q2 and R2 have one of their respective terminals individually attached to four collectors which engage the trolley wires 11, 10, 9, and 8, respectively. These four trolley wires will hereinafter be referred to as main control wires in order to distinguish them from the above-mentioned power supply wires 1, 2, and 3 and the remaining relay control wires 4, 5, 6 and 7. The other terminal of secondary transformer winding Q1 is connected to four relays 1F, 1R, 1A1 and 1A2. These relays, represented in Fig. 2 merely by their control coils, are connected by four collectors with the relay control wires 4, 5, 6 and 7.

In a similar manner, the secondary windings R1 in control panel P1 of trolley E1 and Q2 and R2 in the control panel P2 of the second trolley are connected to three groups of relays denoted by 1H, 1L, 1H1, 1H2; 2F, 2R, 2A1, 2A2, and 2H, 2L, 2H1, 2H2, respectively.

The four main control wires 8, 9, 10, and 11 are individually connected by respective leads 8', 9', 10', and 11' to four master control devices M2, S2, M1, and S1 which are located in the operator's cab. The relay control wires 4, 5, 6, and 7 are connected to each of these four master control devices. Device S1 serves to control the trolley propulsion motor T1 of trolley E1, device M1 effects the control of the hoist motor H1 of trolley E1, while devices S2 and M2 serve for controlling propulsion motor T2 and hoist motor H2, respectively, of trolley E2.

The interconnection of the above-mentioned electric elements and the operation of the system will be more readily understood from the detailed showing in Fig. 3 which refers only to the trolley E1 and the appertaining master control devices S1 and M1.

According to Fig. 3, the propulsion motor T1 is in driving connection through a gear box 12 with the drive wheels 13 of the trolley. The secondary circuit of motor T1 is equipped with resistors 14 and 15, and the relays 1A1 and 1A2, serving as accelerator contactors, operate to short circuit these resistors sequentially under control by the operator. The hoist motor H1 drives the

cable drum 16 through a gear 17 and is similarly equipped in its secondary circuit with resistors 18 and 19 to be short circuited under control by accelerating contactors 1H1 and 1H2.

The primary circuit of motor T1 is connected through leads 21, 22, and 23 and appertaining collectors with the power supply wires 1, 2, and 3, respectively. This connection is under control by relays 1F and 1R which are arranged as reversing contactors. When contactor 1F is energized, the motor T1 is caused to drive the trolley in the forward direction, while the energization of contactor 1R will operate the motor in the reverse direction. The coils of contactors 1A2, 1A1, 1R and 1F have individual circuit leads 24, 25, 26, and 27, respectively, in connection with four corresponding collectors which engage the relay control wires 4, 5, 6, and 7, respectively. The leads 24, 25, 26, and 27 are also in connection with the coils of contactors 1H2, 1H1, 1L, and 1H, respectively. The other coil terminals of relays 1A2, 1A1, 1R and 1F are connected by a common lead 28 with the secondary winding Q1 of transformer N1. Similarly, the remaining coil terminals of the group of relays 1H2, 1H1, 1L and 1H are connected by a common terminal 29 with the secondary winding R1 of the transformer. The primary circuit of the hoist motor H1 is connected by leads 31, 32, and 33 with the power supply wires 1, 2, and 3, respectively, under control by the above-mentioned relays 1H and 1L. Relay 1H is a hoisting contactor and so connected as to operate motor H1 in the hoisting direction when energized, while contactor 1L connects the motor H1 for lowering operation.

It will be noted that in Fig. 3 of the drawings separate collectors are shown for the leads denoted by 21, 22, 23, 31, 32, 33 and the two primary leads of the transformer N1. This manner of illustration is chosen merely for the sake of clarity and convenience, while it is preferred in practice to use only three collectors for all these leads and to attach them properly to the primary circuits of the two motors and of the transformer.

The master control devices S1 and M1, as shown in Fig. 3, correspond to the above described showing in Fig. 2. These master control devices are represented as drum type controllers, each having an "off" position, three steps in the forward or hoist direction and three steps in the reverse or lowering direction.

In the "off" position of the two master controllers, as illustrated in Fig. 3, the two groups of relays appertaining to the motors T1 and H1, respectively, are deenergized because the circuits of the secondary transformer windings Q1 and R1 are interrupted in the master controllers. When controller S1 is placed in the first forward position, the two leads 7 and 11 are connected with each other by the contact fingers and contact segments of this controller. As a result, a circuit is closed from secondary winding Q1 through lead 28, forward contactor 1F, lead 27, relay control wire 7, lead 7', master controller S1, lead 11', and the main control wire 11. Consequently, the relay 1F is energized and closes its contacts, thus causing the motor T1 to start accelerating in the forward direction. When controller S1 is moved to its second forward position, lead 5' becomes connected to lead 11', so that a circuit is closed from the secondary transformer winding Q1 through the trolley wires 5 and 11, thus inserting the accelerating contactor 1A1 into the circuit of winding Q1. Contactor 1A1 closes its contacts and

thereby short circuits the resistor 14 and the secondary circuit of motor T1. When controller S1 is placed in its third forward position, lead 4' and relay control wire 4 become connected to lead 11' and main control wire 11, so that now the accelerating contactor 1A2 is energized through leads 24 and 23 from secondary transformer winding Q1. Contactor 1A2 short circuits the secondary resistors 15, thus causing the motor T1 to accelerate to maximum speed.

When the controller S1 is turned from the "off" position to its "first," "second" and "third" reverse positions, the contactor 1R is energized to operate the motor in the reverse direction, and thereafter the accelerating contactors 1A1 and 1A2 are sequentially energized to short circuit the resistors 14 and 15 in the same manner as described in the foregoing.

When the master controller M1 is moved from its illustrated "off" position to the "first" position hoist, the main control wire 10 is connected through leads 10' and 1'. As a result, the circuit of the secondary winding R1 is closed through lead 27, hoisting contactor 1H, lead 29 and trolley wires 10 and 1. Contactor 1H picks up and starts the hoist motor H1 in the hoisting direction. When controller M1 is moved to its second position hoist, the main control wire appertaining to transformer winding R1 becomes connected to lead 5' and relay control wire 5, so that now the accelerating contactor 1H1 is energized through leads 25 and 29. Contactor 1H1 short circuits the resistors 18 for further acceleration of motor H1. When controller M1 is moved to its third position hoist, lead 4' and trolley wire 4 become connected to the main control wire 10 so that now a circuit is closed which includes the transformer winding R1, the lead 29, the contactor 1H2 and lead 24. Contactor 1H2 short circuits the resistors 19 for full speed operation of the hoist motor H1. When controller M1 is turned from its "off" position to the lowering positions, the contactor 1L becomes energized from transformer winding N1 through main control wire 10 and relay control wire 6. Further details of the controller elements to be effective during the lowering operation are not illustrated in the drawings, because these details are not essential to the present invention and may be given a variety of known designs depending upon particular requirements.

In order to obtain the above described performance of trolley control systems according to the invention, the following conditions should be observed.

Each of the circuit devices represented by transformers N1 and N2 should have its output circuits so connected that the trolley wires 10, 11 or 8, 9, connecting the transformer secondaries with the master controller, have the same instantaneous polarities. This is exemplified by the (+) and (-) signs indicated at the secondary windings R1 and Q1 of transformer N1 in Fig. 3. If this condition is not observed, an undesired voltage-doubling connection will occur which may result in an untimely actuation of all eight illustrated relays appertaining to motors H1 and T1. If this should occur when testing the equipment, the connections of one secondary of one or both transformers need merely be reversed so as to impart to all four main control wires the same instantaneous polarity.

All relays used in the system and controlled through the trolley wires should have about the same pick-up voltage as obtained, for instance, by using relay coils of substantially identical am-

pere turns; or, if some relays are different as regards pick-up voltage, electric interlock contacts (as exemplified and described below) should be provided to secure the above-described proper performance. These alternative conditions will be understood if one considers that aside from the above mentioned operating circuits for the respective relays, some additional parallel connections will occur during the operation of the master control switches. For instance, when in Fig. 3 the master switch S1 is placed in first position forward, the relay 1F will be properly energized from transformer winding Q1. However, a number of parallel circuits will also be closed, such as the one extending from wire 1 through the coils of relays 1H, 1H1 and 1A1 to Q1 and wire 11, lead 11', switch S1, back to wire 1. Another circuit can be traced from wire 1 through relays 2F, 2R, 1R to secondary Q, etc. Hence, aside from the properly energized relay 1F, the other relays will also receive some excitation. Since these other relays, in the first-mentioned parallel circuits, are series-connected in groups of two, three or more, the voltage impressed on the coils of the other relays is considerably below normal. Hence, if all coils are substantially alike and rated to pick up at a voltage above the highest individual voltage drop (42%) occurring within the parallel circuits, only the proper relays will respond in any selected position of the master switches.

As mentioned, if it is desired to use relays with different respective pick-up voltages, an undesired operation of non-selected relays can be prevented by interlocks so arranged that one relay, when responding, disconnects the coil circuits of one or more other relays that are not supposed to operate. Such interlock circuits are well known for relay control systems, and an example will be described presently.

In the embodiment, as shown in Fig. 3, the reversing contactors 1F and 1R are equipped with interlock contacts which prevent one of the accelerating relays 1H1 and 1H2 to become energized simultaneously with the operation of the propulsion motor T1. In this particular instant, the interlocks have the effect that the hoisting or lowering speed of hoist motor H1 is limited to an amount below the normal maximum when a load is hoisted or lowered while the trolley is in simultaneous motion along its track.

Similar interlocks may be arranged between the master controllers, such as S1 and S2 appertaining to different trolleys in order to prevent one from actuating the relays to be controlled by the other if the two trolleys are to operate simultaneously. However, the latter interlocks are not needed if, as in the illustrated embodiment, only one trolley is to operate at a time. These and other details of the illustrated control system are represented for the purpose of explanation and exemplification, and may be modified in various respects within the principles of my invention. For instance, a system according to my invention 55 can readily be extended to more than two trolleys or more than four motors, and each motor can be given a smaller or larger number of accelerating steps than represented in the above described example. It is also obvious that the invention is 60 not limited to alternating-current motors of the illustrated type but is applicable in general to any type motors to be operated through trolley wires or through slip rings such as on Whirley cranes. In addition to the trolley wires discussed above, 65 there are usually some others required for the 70

customary hoist limit switches, travel limit switches, or other protective devices. However, such additional wires would also be used in systems of the conventional type and hence are not pertinent to the present invention.

I claim as my invention:

1. An electric system for controlling a crane trolley from an operator's place remote from the trolley, comprising two reversible alternating-current motors disposed on the trolley for propelling and hoisting operations respectively; two groups of relays disposed on the trolley for controlling said respective motors; transformer means disposed on the trolley and having two output circuits each having two terminals of which one is connected to the relays of one of said groups respectively; a group of trolley wires comprising wires for supplying power to said motors and transformer means and control wires; selective contact means disposed at the operator's place for connecting one of said output circuits through said control wires across the respective relays of one of said relay groups to control said propulsion motor; and selective contact means disposed at the operator's place for connecting said other output circuit through said control wires across the respective relays of said other group of relays to control said hoist motor.

2. An electric system for controlling a crane trolley from an operator's place remote from the trolley, comprising two reversible alternating-current motors disposed on the trolley for propelling and hoisting operations respectively; two groups of relays disposed on the trolley for controlling said respective motors; transformer means disposed on the trolley and having two output circuits each having two terminals of which one is connected to the relays of one of said groups respectively; each relay of one of said groups having an individual lead connected with one of the respective relays of said other group, a group of trolley wires including power supply wires, two main control wires and relay control wires; a group of collectors for engaging said trolley wires including power collectors engageable with said power supply wires and connected to said two motors under control by said respective groups of relays and being also connected to said transformer means for providing energization therefor, two collectors engageable with said main control wires respectively and being connected to said output circuits respectively, and collectors engageable with said relay control wires respectively and connected to said respective individual leads; and two master control means disposed at the operator's place for connecting said respective main control wires selectively with said relay control wires for individually controlling said two motors.

3. An electric system for controlling a crane trolley from an operator's place remote from the trolley, comprising a reversible trolley propulsion motor and a reversible hoist motor disposed on the trolley; a first group of relays disposed on the trolley for controlling said trolley motor and comprising two selectively operable reversing contactors; a second group of relays disposed on the trolley for controlling said hoist motor and comprising two selectively operable reversing contactors; circuit means disposed on the trolley and having two output circuits for energizing said relay group respectively, each of said group of relays having a common lead connected to one of said output circuits respectively and each of said relays having an individual lead; a group of trolley wires including power supply wires, two main

control wires and two relay control wires; a group of collectors for engaging said trolley wires including power collectors engageable with said power supply wires and connected to said two motors under control by said respective groups of relays and being also connected to said circuit means for providing energization therefor, two collectors engageable with said main control wires respectively and being connected to said output circuits respectively, and two collectors engageable with said relay control wires respectively and being each connected to said individual lead of one of said first group of relays and also to said individual lead of one of said second group of relays; trolley master control means disposed at the operator's place and connected to said two relay control wires and to the one main control wire appertaining to the one output circuit connected to said first group of relays for controlling said trolley motor by selectively closing said one output circuit through said relays of said first group, and hoist master control means disposed at the operator's place and connected to said two relay control wires and to the other main control wire for controlling said hoist motor by selectively closing said other output circuit through said relays of said second group.

4. An electric system for controlling a crane trolley from an operator's place remote from the trolley, comprising two wound rotor motors disposed on the trolley for propelling and hoisting operations respectively and having each a primary circuit and a secondary resistance circuit; two groups of relays disposed on the trolley for controlling said respective motors, each of said groups having a forward contactor and a reverse contactor for selectively controlling the primary circuit and at least one accelerating relay for controlling the secondary circuit of the appertaining motor; transformer means disposed on the trolley and having two secondary windings each having two terminals of which one is connected to all said relays of one of said relay groups respectively; a group of trolley wires comprising power supply wires for said motor primary circuit and said transformer means, two main control wires in conductive connection with said other terminals of said respective secondary windings, and relay control wires in conductive connection with said two forward contactors, said two reverse contactors and said accelerating contactors respectively; and two master control means disposed at the operator's place for connecting said respective main control wires selectively with said relay control wires for individually controlling said two motors.

5. An electric system for controlling a plurality of crane trolleys from a single operator's place, comprising two reversible motors disposed on each trolley for trolley propulsion and hoisting operations respectively; two groups of relays disposed on each trolley for controlling said respective motors; circuit means disposed on each trolley and having two output circuits each having two terminals of which one is connected to the relays of one of said respective groups of relays; a group of trolley wires including power supply wires for energizing said motors and said circuit means, a number of main control wires corresponding to the total number of said output circuits and individually in conductive connection with said respective other terminals of said output circuits, and relay control wires in conductive connection with the respective relays of each of said relay groups; and selective master control

means for each of said trolleys disposed at the operator's place for individually connecting the two main control wires that appertain to each trolley with said relay control wires for individually controlling said two motors of each trolley.

6. An electric system for controlling a plurality of crane trolleys from a single operator's place, comprising two reversible alternating-current motors disposed on each trolley for trolley propulsion and hoisting operations respectively; two groups of relays disposed on each trolley for controlling said respective motors; transformer means disposed on each trolley and having each two secondary windings, each of said secondary windings having two terminals of which one is connected to the relays of one of said respective group of relays; a group of trolley wires including power supply wires for energizing said motors and said transformer, a number of main control wires corresponding to the total number of said secondary windings and individually in conductive connection with said respective other terminals of said secondary windings, and relay control wires each being in conductive connection with a plurality of relays appertaining to different ones of said relay groups; and selective master control means for each of said trolleys disposed at the operator's place for individually connecting the two main control wires that appertain to each trolley with said relay control wires for individually controlling said two motors of each trolley.

7. An electric system for controlling a plurality of crane trolleys from a single operator's place, comprising two reversible wound rotor motors disposed on each trolley for propelling and hoisting operations respectively and having each a primary circuit and a secondary resistance circuit; two groups of relays disposed on each trolley for controlling said respective motors, each of said relay groups having a forward contactor and a reverse contactor for selectively controlling the primary circuit and at least one accelerating relay for controlling the secondary circuit of the appertaining motor; transformer means disposed on each trolley and having two secondary windings each having two terminals of which one is connected to all said relays of one of said relay groups respectively; a group of trolley wires

comprising power supply wires for said motor primary circuit and said transformer means, a number of main control wires corresponding to the total number of said secondary windings and individually in conductive connection with said respective other terminals of said secondary windings, and relay control wires each being in conductive connection with a plurality of relays appertaining to different ones of said relay groups; and selective master control means for each of said trolleys disposed at the operator's place for individually connecting the two main control wires that appertain to each trolley with said relay control wires for individually controlling said two motors of each trolley.

8. An electric control system for controlling two trolleys of a bridge crane from an operator's place, comprising two three-phase wound rotor motors disposed on each trolley for propelling and hoisting operations respectively and having each a primary circuit and a secondary resistance circuit; two groups of relays disposed on each trolley for controlling said respective motors, each of said relay groups having a forward contactor and a reverse contactor for selectively controlling the primary circuit and first and second accelerating relays for controlling the secondary circuit of the appertaining motor; transformer means disposed on each trolley and having each two secondary windings, each of said secondary windings having two terminals of which one is connected to the relays of one of said respective group of relays; a group of eleven trolley wires including three power supply wires for said motors and said transformers, four main control wires for connection to said other terminals of said four secondary windings respectively, and four relay control wires in conductive connection with said forward contactors, reverse contactors, first accelerating contactors and second accelerating contactors respectively; and selective master control means for each of said trolleys disposed at the operator's place for individually connecting the two main control wires that appertain to each trolley with said relay control wires for individually controlling said two motors of each trolley.

REMI BOLLAERT.
